MEANS FOR RETRACTING THE CORES FROM
THE ELECTROMAGNETS OF A MAGNETIC
SOUND RECORDING HEAD

Donald E. Ross, Eagle Rock, and Herman S. Heller, Los Angeles, Calif.; said Ross assignor to said Heller

Application April 26, 1947, Serial No. 744,190

13 Claims. (Cl. 179—100.2)

1

This invention relates generally to recording and reproducing equipment of the magnetic type, and more particularly to coil assemblies for use with such equipment in which the pole pieces of the magnet are moved toward or away from a tape when the latter is to be inserted or removed.

In the construction of magnetic recorders and reproducers making use of a ferromagnetic tape as the recording medium, it is desirable to be able to replace the tape with a single simple operation. In the copending application of the present inventors, entitled "Removable Magazine For Tape," Serial No. 720,217, filed January 4, 1947, a magazine has been disclosed which may be quickly and easily removed from the translating device, and while the present invention is preferably used in combination with this magazine, it may be also used with other magazines and devices as will become apparent.

In the recording and reproducing of sound on a magnetic tape, the latter may advantageously be enclosed within a guide having openings therein to receive the pole tips of the electromagnets used in the translation of sound. Consequently it is necessary to separate these pole tips from the tape and the guide if the latter are to be inserted and removed without damaging the pole tips. Preferably this separation and return of the pole tips is accomplished simultaneously with the release of a locking assembly holding the magazine in position, and additionally, these two operations should be accomplished by a single operation of the mechanism. It will be realized that the mechanical separation of the pole tips may be accomplished in a number of ways, but practical considerations arise which impose additional restrictions upon such a separating means. For example, where the recording is of the multiple lane type wherein a plurality of laterally disposed lanes are recorded along the length of the tape, the pole tips must be transversely movable across the tape in a predetermined number of steps corresponding to the number of lanes, and the registration of the pole tips with each of these lanes must be very accurately maintained. Nevertheless, the pole tips must be instantly separable regardless of their lateral position with respect to the tape.

It is, therefore, a major object of this invention to provide a pole separating means for electromagnets which will simultaneously separate a plurality of electromagnet pole tips for the insertion or removal of a member therebetween.

Another object of the invention is to provide

such a separating means which may be quickly and easily operated by an inexperienced operator with a minimum of effort.

It is a further object of this invention to provide such a device in which the pole tips are maintained in a predetermined position with respect to the carrying member, even though the latter may be movable across the width of the tape.

Still another object of the invention is to provide such a device which is mechanically simple yet positive in operation.

It is a still further object to produce a device of this type which, while having all of the features mentioned above, may be produced at a cost which is low, having regard for the precision of the work which is to be done.

These and other objects and advantages of the invention will become apparent from the following description of a preferred form thereof, and from the drawings illustrating that form, in which:

Figure 1 is a plan view of a device herein shown as a magnetic sound translator, making use of the improved pole separating mechanism, with the type magazine removed and with the locking handle raised to show the translating and erasing head and the control head;

Figure 2 is a cross-sectional view through the upper portion of the device taken at 2—2 in Figure 1;

Figure 3 is a cross-sectional view through one of the pairs of electromagnets in the erasing and translating head, taken at 3—3 in Figure 1, with the locking handle raised and the pole tips in retracted position.

Figure 4 is a view similar to Figure 3 but with the locking handle lowered and the pole tips in extended or operating position;

Figure 5 is a perspective view of a portion of the operating mechanism used to retract and extend the pole tips shown in Figures 3 and 4;

Figure 6 is a horizontal sectional view taken at 6—6 in Figure 4, and showing the method of supporting a portion of the operating mechanism shown in Figure 5;

Figure 7 is a cross-sectional view through a pair of electromagnets of the control head, taken at 7—7 in Figure 1 and showing the locking handle in raised position, with the pole tips retracted;

Figure 8 is a perspective view of the pole tip operating mechanism used in conjunction with the electromagnets of the control head; and

Figure 9 is an exploded perspective view of the

2

handle and locking assembly, showing the operating elements in their retracted position.

Referring now to the drawings and particularly to Figure 1 thereof, the numeral 10 indicates generally a housing enclosing a motor, an amplifier, controls for these units, and other miscellaneous equipment associated with a sound recording and reproducing device. The upper portion of the housing 10 is closed by a top or cover 11 through which couplings 12 project to engage corresponding coupling members of a removable magazine (not shown) and on which a slidable bolt 13 is mounted to engage and lock the magazine in position. While it is to be understood that the herein disclosed apparatus may be used in different devices adapted to receive different types of tape-holding means, in the exemplification shown, the apparatus is adapted to be used with a magazine such as that shown in the previously mentioned copending application of the present inventors. As disclosed in that application, the magazine (not shown) is provided with a re-entrant section along its rear edge adapted to receive a sound translating and erasing head 14 and a control head 15. The magazine is also preferably furnished with a tape-guiding means, hereinafter described in greater detail, which surrounds and guides the tape in its passage through the translating and control heads 14 and 15.

Mounted on the cover 11, adjacent the sides of the translating and control heads 14 and 15, are a pair of upstanding ears 16 to which an operating handle 17 is attached for movement about a horizontal axis. The ears 16 are located near the rear of the translating and recording heads 14 and 15, and a pair of arms 18 are pivotally attached to the ears and extend to the handle 17 so that when the latter is rotated to its lowermost position, the arms 18 assume a horizontal position extending forwardly to a point in front of the heads 14 and 15. When the handle 17 is moved upwardly, the arms 18 swing about their pivotal connections to the vertical position shown in Figures 1 and 2. The heads 14 and 15 are thus surrounded by the arms 18 and handle 17 when the latter are in their lowered position, and a cover 20 is mounted between the arms 18 to cooperate with a magnetic shield or enclosure 21 mounted on the top 11 to enclose the heads and protect them from the influence of external magnetic fields when the handle 17 is lowered.

In order that the slidable bolt 13 may be operated to release the magazine (not shown) simultaneously with the raising of the handle 17, the arms 18 are extended away from the handle, beyond the ears 16, and are provided with horizontally extending pins 22 at their free ends to fit within slots 23 of upwardly extending bifurcated members 24, shown in Figures 4 and 9. From these figures it will be seen that as the pins 22 rotate about the pivotal axis of the arms 18, the former will be moved forwardly as the handle 17 is raised, and will be moved rearwardly as the handle is lowered.

Rigidly connected to the bifurcated members 24 is a U-shaped plate 25 which is slidably mounted on the cover 11 and which has a forwardly extending projection 26 which carries the slidable bolt 13. The base of the U-shaped plate is located forwardly of the translating and control heads 14 and 15, while the arms of the plate extend rearwardly on each side of the heads to connect to the bifurcated members 24. Forward and rearward motion of the pins 22 is thus trans-

mitted from the bifurcated member 24 to the slidable plate 25 so that the slidable bolt 13 is moved forwardly when the handle 17 is raised to the position shown in Figures 1, 2 and 3, and is moved rearwardly with respect to the housing 10 when the handle is lowered, as shown in Figure 4. It is to be understood, of course, that the magazine (not shown) is designed to be locked in place by the rearward movement of the bolt 13, and to be released by the forward movement of the latter.

The translating and erasing head 14 and the control head 15 consist essentially of electromagnets having cores with very narrow pole tips which bear against the magnetic tape to magnetize the latter or to be magnetically affected thereby to produce a signal. The fundamentals of operation of such a system are well known and will not be repeated here. The signal which is magnetically recorded upon the tape may be adapted to operate a loud speaker or any sort of control or indicating equipment desired. It will be realized, of course, that the use of such a system is not restricted to the recording and reproducing of sound, but may be extended to any phenomenon which may be caused to vary the magnetic strength or field intensity of an electromagnet.

In order that the operation of the device may be simplified, certain functions, such as the reversal of direction of tape travel, etc., are performed automatically in response to signals recorded on the tape and detected by the control head 15. This head is quite similar to the translating and erasing head 14, but for the sake of clarity, the heads will be separately described, the translating and erasing head being described first. The latter includes a plurality of identical pairs of electromagnets, one of which is shown in cross-section in Figures 3 and 4 and which will now be described.

As shown in these figures, the head 14 includes a pair of electromagnets 30 and 31 having coils 32 and 33, respectively, surrounding magnetic cores 34 and 35, respectively. The electromagnets 30 and 31 are mounted within a housing 36 so that their coils 32 and 33 are axially aligned, and in the form shown, the cores are horizontal, parallel to the top 11. A laterally extending vertical slot 37 is formed within the housing 36 between the electromagnets 30 and 31 so that the adjacent ends of the cores 34 and 35 may extend into the slot from opposite sides thereof. A tape 40 having suitable magnetic properties may be inserted in the slot 37, and a tape guide 41 is preferably used to support and guide the tape during the latter's passage through the heads 14 and 15. The guide 41 surrounds the tape 40 and is provided with suitable apertures or slots there-in so that the tips of the cores 34 and 35 may bear against the opposite faces of the tape 40, this guide preferably being of the type shown and described in the previously mentioned copending application of the present inventors. In the presently described form of the invention, it will be apparent that the tape 40 moves in a direction perpendicular to the plane of the drawing in its passage between the core members 34 and 35.

In order that the lineal speed of the tape may be kept within practical limits while permitting the accurate recording and reproduction of higher frequencies, it is necessary that the tips of the cores 34 and 35 which bear against the tape be very narrow in the direction of tape travel. How-

ever, in order that a sufficient amount of tape may be magnetized, it is important that the width of the tips be considerably greater in the direction perpendicular to the direction of tape travel. Consequently, it is desirable that the cores 34 and 35 be of the general type shown in the copending application of Herman S. Heller, Serial No. 696,157, filed September 11, 1946, now Patent No. 2,514,577, for "Magnetic Recorder Pole Piece." As disclosed in this application, the cores 34 and 35 include a series of longitudinally extending laminations encased in a non-magnetic shell 42 of non-circular cross section. At one end of the core, the laminations are reduced in number and/or thickness so that pole tips 44 and 45 are formed, having a magnetic portion of very narrow width and only slightly reduced height which bears against the tape 40. The pole tips 44 and 45 are very accurately aligned with each other, and in this way a very high concentration of magnetic flux is produced within a very limited area of the tape 40. Since, as mentioned, it is necessary that the larger dimension of the pole tip extend transversely across the tape in a direction perpendicular to the travel of the latter, the shells 42 for the cores 34 and 35 are preferably formed of a non-circular cross section as mentioned, so that they may be inserted within the electromagnets 30 and 31 only when the pole tips 44 and 45 are properly oriented. This, of course, requires a correspondingly shaped central recess or aperture within the electromagnets 30 and 31 to receive the cores 34 and 35.

To urge the pole tips 44 and 45 against the tape 40, the opposite ends of the cores 34 and 35 are provided with enlarged heads 46 and 47 respectively, and springs 50 and 51 are mounted to bear against the housing 36 and the corresponding heads to urge the cores inwardly. It is to be expected, of course, that the pole tips 44 and 45 will be worn by their constant rubbing against the tape 40 and hence provision has been made for the replacement of the cores 34 and 35 when the tips become worn. In the presently described embodiment, this has been done by inserting screw-threaded plugs 52 and 53 in the housing 36 so that the plugs are aligned with the cores 34 and 35, and the outer ends of the springs 50 and 51 bear against the corresponding plugs. The diameter of the plugs 52 and 53 is slightly larger than the heads 46 and 47 so that it is a simple matter to remove the magnetic shielding 21, unscrew the plugs 52 and 53 and remove the worn cores 34 and 35, replace the latter, and then reassemble the unit.

It will be appreciated that the axial alignment of the pole tips 44 and 45 is a very important consideration, and the permissible tolerances in aligning these tips must be held to a very small amount. The alignment of the pole tips 44 and 45 will be determined by the members supporting the cores 34 and 35 and particularly the members supporting the adjacent ends of those cores. While the central portion of the shells encasing the cores 34 and 35 is preferably rectangular, as previously explained, the pole tips 44 and 45 are preferably encased within a housing or shell portion having a circular cross section since this permits the aperture through which they extend to be circular. In the construction illustrated, the housing 36 is provided with adjacent walls 54 on opposite sides of the slot 37, and aligned apertures 55 are formed in these walls to receive the adjacent ends of the cores 34 and 35. As is well-known, it is much easier to form accurately

located and dimensioned circular holes than those of any other shape, and in this way it is possible to secure every accurate alignment of the pole tips 44 and 45 while retaining the advantages of the non-circular cross-sectional shape of the body of the cores 34 and 35. The opposite ends of the cores 34 and 35 are supported by plates 56 attached to the housing 36 and acting both to support the cores and to retain the coils 32 and 33 in their correct locations. The apertures formed in the plates 56 for the reception of the cores 34 and 35 will, of course, be shaped to hold the cores with a minimum of looseness and wobbling, but any excess clearance between the edges of the holes and the corresponding cores will have a much smaller effect upon the alignment of the pole tips 44 and 45 than a corresponding clearance between the apertures 55 and the adjacent ends of the cores.

While the springs 50 and 51 normally urge the cores 34 and 35 toward each other so that the pole tips 44 and 45 bear against opposite surfaces of the tape 40, it is desirable, as mentioned, to be able to separate or retract the pole tips so that they no longer extend into the slot 37 when the tape is to be removed or replaced. This is particularly necessary where the tape 40 is enclosed within a tape guide 41 since movement of the latter into and out of the slot 37 will normally cause it to bear against the ends of the cores 34 and 35 and thereby destroy the accurate alignment of the pole tips 44 and 45. Since the handle 17 must be raised to release the bolt 13 from the magazine (not shown) preparatory to the removal and/or replacement of the tape 40 and its guide 41, the operation of the device will be simplified if the same raising of the handle is effective to retract the pole tips 44 and 45 to a position where they are flush with the adjacent surfaces of the walls 54. In order to accomplish this the retracting mechanism now to be described has been developed.

Slideably mounted within the housing 36 is an operating member 60 having a generally T shape with the stem 61 of the T being disposed horizontally, parallel to the axis of the cores 34 and 35. One side 62 of the cross bar of the T extends in a direction generally downward from the stem 61 while the other side 63 of the cross bar extends upwardly from the stem 61 to a point adjacent the outer end of the core 35. While it will become apparent that with very simple modifications the pole tip separating mechanism may be reversed so that the operating member 60 is adjacent the head 46 of the core 34 instead of the head 47 of the core 35, it has been found that very satisfactory results are obtained by having the operating member act directly on the head 47 in the manner now described.

Mounted on the upper end of the section 63 of the cross bar is an angular member 64, having a generally horizontally extending flange attached to the upper end of the section 63, and having a generally vertically extending flange adapted to fit beneath the head 47. The vertically extending flange of the angle 64 fits between the wall 56 and the adjacent side of the head 47 so that movement of the operating member 60 forwardly, away from ears 16 and toward the slidable bolt 13, will move the head 47 in the same direction, thereby moving the core 35 away from the tape 40 and simultaneously compressing the spring 51 against the plug 53. It will be remembered that there are a plurality of electro-magnets and associated cores within the translating and eras-

ing head 14, and the angle member 64 is made of a sufficient length to engage all of the heads corresponding to the head 41 of the core 35, and simultaneously retract all of them.

To retract the pole tip 44 from the opposite side of the tape 40 simultaneously with the retraction of the pole tip 45 in the manner just described, the free or unattached end of the stem portion 61 of the operating member 60 is connected to the head 46 of the core 34 by means of a pivoted lever so that movement of the stem in one direction causes the movement of the core in the opposite direction. As indicated in Figures 3 to 5, the free end of the stem 61 is provided with a notch 65 in its upper surface adapted to receive a pivoted plate 66. The latter extends downwardly into the notch 65 from a pivotally mounted shaft 67 whose ends are supported by the housing 36, as illustrated in Figure 6. The notch 65 will normally be somewhat wider than the thickness of the plate 66 in order that the latter may rotate freely about a slight angle as the operating member 60 is moved forwardly and rearwardly. A second rotatable plate 68 is attached to the shaft 67 for rotation therewith, and extends upwardly from the shaft to a point adjacent the core 34 of the electro-magnet 36. As indicated in Figures 3 and 4, the upper rotatable plate 68 may be provided with an offset section to enable it to fit snugly between the head 46 of the core 34 and the wall 36. The spring 58 will normally urge the head 46 toward the tape 40, rotating the upper rotatable plate 68 in a clockwise direction as seen in Figure 3, and urging the lower rotatable plate 66 toward the rear of the housing 36, thereby urging the operating member 60 in the same direction. It will be noted that the spring 51 likewise urges the angle member 64, and hence the operating member 60, rearwardly, and thus the springs 50 and 51 cooperate to urge the pole tips 44 and 45 toward each other, while simultaneously urging the operating member 60 toward the rear of the housing. The retraction of the pole tips 44 and 45 may be accomplished by moving the operating member 60 toward the front of the housing, to the right in Figures 3 and 4, thereby moving the angle member 64 to overcome the urging of the spring 51, and simultaneously pivoting the upper and lower rotatable plates 68 and 66 about their shaft 67 in a counter-clockwise direction so that the head 46 is moved against the urging of the spring 58, to the left in Figures 3 and 4.

It will be noted that to retract the pole pieces 44 and 45, the operating member 60 is moved forwardly with respect to the housing 10, which is the same direction that the bolt 13 and the slidable plate 25 are moved when the handle 17 is moved to the position shown in Figure 3, preparatory to replacing the tape 40. Likewise, to extend the pole tips 44 and 45 so that the latter bear against the tape, the operating member 60 is moved rearwardly, this being in the same direction that the slidable bolt 13 and plate 25 are moved when the handle 17 is lowered to the position shown in Figure 4 to lock the magazine (not shown) in place. The movement of the slidable bolt 13, however, is much greater than the necessary movement of the operating member 60, and hence some form of motion reducing system must be provided if the movement of the slidable plate 25 is to drive the operating member 60. In addition, it will be seen that it is desirable to retract the pole tips 44 and 45 immediately upon starting to raise the handle 17,

and similarly they should not be extended to bear against the tape 40 until just before the handle reaches its lowermost position. In this way, there is very little chance that the pole tips 44 and 45 will extend into the slot 37 where they may be hit or moved by the tape guide 41 when the latter is being removed or inserted into the slot. These two conditions indicate the desirability of a lost motion linkage between the slidable plate 25 and the operating member 60, and such a device has been provided.

As indicated in Figure 9, the base of the U-shaped plate 25 is provided with elongated slots 70 whose axes are parallel to the direction of movement of the plate 25. Each slot 70 is adapted to receive a pin 71 which is mounted on a slidable push-plate 72 mounted beneath the cover plate 11. A spacing plate 73 is attached to the cover 11 beneath the heads 14 and 15, and the rear end of the push-plate 72 is offset from the cover to bear against the lower surface of the spacing plate. The forward end of the push-plate 72 bears against the undersurface of the cover 11, and a shoulder 74 is formed by reason of the offset positions of the forward and rear edges of the push-plate. Holes 75 are formed in the shoulder 74 to receive a pair of horizontal guide rods 76 which are attached to the forward edge of the spacing plate 73, and helical compression springs 77 are placed over the guide rods 76 to bear against the forward edge of the spacing plate 73 and the rear surface of the shoulder 74. The lower ends of the pins 71 are attached to the portion of the push-plate 72 rearwardly of the shoulder 74 and forwardly of the spacing plate 73, being held thereto by nuts 78 or other suitable means, and the pins thus move with the push-plate.

When the handle 17 is raised and the slidable plate 25 is in its most forward position, the pins 71 bear against the rear ends of the slot 70 and the helical springs 77 thus urge the push-plate forwardly. However, as the handle 17 is rotated to its lowermost position, the slidable plate 25 is moved rearwardly until such time as the forward ends of the slots 70 bear against the pins 71 and force them and the push-plate 72 rearwardly against the urging of springs 77. By the correct designing of the various elements, it is possible to cause a sliding movement of the push-plate 72 of approximately $\frac{1}{8}$ ", whereas the slidable plate 25 moves a distance of $\frac{1}{2}$ ". It is to be understood, of course, that these distances are by way of example only and have been found most satisfactory for the particular design of sound translating equipment herein described. Furthermore, it will be seen that the push-plate 72 is moved rearwardly during the last portion of the downward travel of the handle 17, and is moved forwardly by the springs 77 during the first portion of the upward movement of the handle. Consequently, movement of the push-plate 72 occurs only when the handle 17 is substantially in its locked or lowermost position.

To aid in holding the slidable plate 25 to the cover 11, the pins 71 may be provided with heads 80 or other suitable holding means to bear against the upper surface of the slidable plate and thereby hold the latter and the push-plate 72 on opposite sides of the cover. The push-plate 72 may additionally be held to the spacing plate 73 by screw 81 or other suitable means which pass through slots 82 within the push-plate.

Near its rear edge, the push-plate 72 is provided with a pair of slots 83 and 84, of which the

slot 33 is adapted to receive the lower section 62 of the cross bar of the operating member 60. The size and shape of the slot 33 is such as to engage the section 62 with a relatively close fit which prevents any material horizontal movement between the two, while permitting vertical movement of the latter with respect to the push-plate.

As previously mentioned, it has been found desirable to use a plurality of laterally displaced lanes or recording areas within a single tape in a recording and reproducing device of this type, and a complete translation system using this principle is shown in the copending application of Herman S. Heller, Serial No. 608,734, filed August 3, 1945, now Patent No. 2,468,198, granted April 26, 1949, and entitled "Tape Type Sound Recording and Reproducing Machine." The present invention is intended for use in such a system, and consequently provision must be made for shifting the relative position of the pole tips 44 and 45 transversely with respect to the tape 40. In general, it is not practical to shift the position of the tape itself, and consequently the position of the pole tips 44 and 45 is shifted with respect to the tape by raising or lowering the head 14 with respect to the tape and the top 11. This may be accomplished by mounting the housing 36 upon a plate 85 which is carried by the upper end of a vertically extending post or column 86. The latter is mounted for vertical movement with respect to the top 11, and its position may be determined by a ratchet or stepping arrangement such as that disclosed in the copending application of Herman S. Heller, Serial No. 608,734. Since this positioning device forms no part of the present invention, it is not illustrated, and the lower end of the post 86 is shown as being broken away, it being understood that the post continues on downwardly to the particular form of positioning apparatus used. As the post 86 is moved upwardly or downwardly, the pole tips 44 and 45 will of course be correspondingly moved transversely across the tape 40. By the proper design, the tips may be moved across a tape of any desired width in steps of any desired size, and in Figures 3 and 4 it will be noted that the pole tips 44 and 45 bear against the tape 40 in an area near its center, there being other lanes with which the tips may be caused to register by moving the post 86 upwardly or downwardly.

As the housing 36 is raised and lowered with respect to the top 11, it will be apparent that the operating member 60 will be moved vertically with the housing. Since the handle 17 may be raised to the position shown in Figure 3 when the pole tips 44 and 45 are aligned with any one of the various laterally displaced lanes on the tape 40, it is important that the pole tips be retracted by the operation of the handle 17 regardless of their lateral alignment with the tape.

The need for the slidable fit between the portion 62 of the operating member 60 and the push-plate 72 will now become apparent. When the operating member 60 is moved rearwardly, to the left in Figures 3 and 4, the cores 34 and 35 are moved toward each other in the manner previously described and the pole tips 44 and 45 bear against opposite faces of the tape 40. When the operating member 60 is moved forwardly, to the right in Figures 3 and 4, the pole tips 44 and 45 are retracted, leaving the slot 31 unobstructed so that the tape 40 and tape guide 41 may be freely moved therein. The extension and retraction of the pole tips 44 and 45 will occur in this manner

whenever the operating member 60 is moved, regardless of the vertical distance of the housing 36 above the top or cover 11. The push-plate 72, by reason of its lost motion connection to the slidable plate 25, is adapted to provide the necessary horizontal movement of the operating member 60 but is held against vertical movement. Consequently, the previously described slidable connection between the two transmits the horizontal movement of the push-plate 72 to the operating member 60 while permitting the latter to be moved vertically with the housing 36. As a result, the pole tips 44 and 45 are retracted whenever the handle 17 is raised to its uppermost position, and similarly the pole tips are extended when the handle is placed in its lowermost position, regardless of the distance of the housing 36 above the cover 11. It will be realized, of course, that all of the pole tips of the various pairs of electro-magnets within the translating and recording head 14 will simultaneously be retracted and extended, whether there are two, three, or any other number of pairs of electro-magnets within the head.

As previously mentioned, the presently described apparatus has certain of its functions controlled by signals recorded on the tape 40, and hence there is provided a control head 15 which is illustrated in detail in Figures 7 and 8. It will be noted that the control head 15 is similar in many respects to the translating and erasing head 14 previously described, with the exception that the vertically movable post 86 is omitted, and the housing 36a, corresponding to the housing 36 of the translating and erasing head, is firmly attached to the top 11. For clarity and ease of understanding, the parts shown in Figure 7 which correspond to those shown in Figures 4 and 5 have been given the same reference numerals with the letter *a* added thereto. Thus, the housing 36a encloses a pair of electro-magnets 30a and 31a consisting of windings 32a and 33a respectively, surrounding cores 34a and 35a. These cores have pole tips 44a and 45a which bear against opposite faces of the tape 40 enclosed within the tape guide 41. The latter two elements, it will be appreciated, are the same elements which appeared in Figures 3 and 4 illustrating the translating and erasing head, and merely continue through both the heads 14 and 15. The opposite ends of the pole pieces 44a and 45a are provided with heads 46a and 47a which are urged toward the tape 40 by springs 50a and 51a. An operating member 60a is mounted within the housing 36a, and is provided with a generally horizontally extending stem portion 61a and a downwardly extending section 62a of a cross bar. Substantially aligned with the latter is an upwardly extending section 63a of the cross bar, provided with an angle 64a at its upper end. The free end of the stem 61a is provided with a notch 65a into which fits a pivoted plate assembly comprising a pair of plates 66a and 68a mounted on a shaft 67a. It will be appreciated that the cores 34a and 35a are similar to the cores 34 and 35 of the first described head and electro-magnets 30a and 31a are so constructed that the pole tips 44a and 45a will be aligned with each other and oriented with respect to the tape 40 in a manner similar to that previously described.

However, as previously mentioned, the control head 15 is not intended to be movable transversely across the tape 40, and hence all of the pairs of electro-magnets within this head must

be permanently aligned with the particular lane with which they are to cooperate. If there are two lanes which are to be used for signal or control purposes, there will normally be one pair of electro-magnets within the control head 15 for each of these lanes. In addition, since these lanes are laterally displaced with respect to the tape, the pole tips of the corresponding pairs of electro-magnets will likewise be laterally displaced with respect thereto, and consequently one pair of electro-magnets will be further above the top 11 than the other. Since the pole tips of both pairs of electro-magnets are to be retracted simultaneously, they should both be operated by the angle member 64a and the pivoted plate 68a. Because of the difference in elevation above the top 11, however, the cores of one pair of electro-magnets will not be aligned with those of the other pair, and consequently it is desirable to notch the angle 64a and the pivoted plate 68a to form recesses 90 and 91, respectively, to receive the corresponding cores. These notches 90 and 91 are shown in Figure 8, where it is seen that they permit the simultaneous operation of two pairs of laterally displaced cores with a minimum of parts.

The operation of the operating member 60a, with the exception just noted, is identical with that previously described in connection with the translating and erasing head 14, and the operating head 15 is actuated by the engagement of its lower cross bar section 62a which fits into the slot 84 of the push-plate 72. As in the case of the corresponding members of the translating and erasing head 14, the lower cross bar section 62 fits within the slots 84 with a relatively snug fit which nevertheless permits vertical movement of the operating member 60a with respect to the push-plate 72. While the control head 15 is not intended to be raised and lowered with respect to the top 11, for ease in assembly and maintenance it is advisable to have the head and its operating member 60a readily disengageable from the push-plate 72 in case the head must be repaired or replaced.

From the foregoing, it will be seen that a magnetic coil and pole tip assembly has been provided for use in magnetic sound translators, particularly those of the multiple lane type. By a single, simple operation of the handle 17, the tape magazine (not shown) is released and the pole tips are retracted so that the magazine and the tape and guide carried thereby may be easily and quickly removed from the recording and reproducing device. In a similar manner, the reverse movement of the handle locks the magazine in place and extends the pole tips so that they bear against opposite faces of the tape, while assuring that their accurate alignment is maintained at all times. Furthermore, this retraction and extension of the pole tips may be accomplished at any time, without regard to the transverse position of the translating and erasing head 14 with respect to the tape 40.

While a preferred embodiment of this device has been shown, it will be realized that modifications may be made therein without departing from the spirit of the invention as herein defined, and the latter is not to be limited to the particular construction or arrangement of parts herein described and shown except as covered by the claims.

We claim:

1. A device for retracting the pole tips of a pair of electro-magnets from an element between

them, which includes: a core in each of said electro-magnets attached to the corresponding pole tip thereof; an operating member movable in a direction parallel to the desired movement of one of said pole tips; means connecting said operating member to the corresponding core of said pole tip; and pivoted means interconnecting said member and said remaining core whereby movement of said member in one direction moves said remaining core in the opposite direction, thereby separating said pole tips.

2. A device for retracting the pole tips of a pair of electro-magnets from an element between them, which includes: a core in each of said electro-magnets attached to the corresponding pole tip thereof; an operating member movable in a direction parallel to one of said cores; means connecting said operating member to said last-mentioned core, whereby movement of said member in one direction moves said core and its associated pole tip in the same direction; pivoted means interconnecting said member and said remaining core, whereby movement of said member in one direction moves said remaining core and its associated pole tip in the opposite direction, thereby separating said pole tips; and resilient means urging said cores and said pole tips together.

3. A device for retracting the pole tips of a pair of electro-magnets from an element between them, which includes: a movable core in each of said electro-magnets attached to the corresponding pole tip thereof; an operating member movable in a direction parallel to the movement of one of said cores; an enlargement formed on each of said cores; resilient means urging said enlargements and the pole tips associated therewith together, whereby said pole tips bear against said element; means bearing against one of said enlargements and operable to move the pole tip associated therewith away from said element, against the urging of said resilient means, said means being connected to said member for operation thereby; and pivoted means bearing against the other of said enlargements and connected to said member to move the other of said pole tips in the opposite direction, against the urging of said resilient means, away from said element, whereby movement of said member in one direction separates said pole tip, and movement in the opposite direction returns said pole tips toward said element.

4. A device for separating the pole tips of a pair of electro-magnets adapted to be moved across an element between them, which includes: a supporting member; a housing mounted on said supporting member and movable with respect thereto; a pair of electromagnets within said housing having cores with adjacent pole tips axially movable relative to said electromagnets and adapted to bear against opposite sides of said element and move with said housing thereacross; an operating member movable in a direction to retract one of said pole tips relative to its electromagnet; means connecting said member to said pole tip to retract the latter; pivoted means interconnecting said member and said remaining pole tip whereby movement of said member in one direction moves said remaining pole tip in the opposite direction relative to its electromagnet, thereby separating said tips without moving said electromagnets; and slidably means mounted on said supporting member for movement in a direction substantially perpendicular to that of said housing, slidably connected

to said operating member, whereby movement of said slidable member acts to separate said pole tips regardless of the position of said housing.

5. A device for separating the pole tips of a pair of electromagnets adapted to be moved across an element between them, which includes: a supporting member; a housing mounted on said supporting member and movable with respect thereto; a pair of electro-magnets within said housing having cores with adjacent pole tips adapted to bear against opposite sides of said element, said pole tips being movable with said housing across said element; an operating member mounted within said housing for sliding movement in a direction generally parallel to the axes of said cores; an arm attached to said operating member and extending in a direction substantially parallel to the direction of movement of said housing; an enlarged head formed on each of said cores; spring means bearing against said housing and said heads to urge said cores and said pole tips toward said element; means rigidly connected to said operating member and extending beneath one of said heads to urge the latter and its associated core away from said element against the urging of said spring means; means pivotally attached to said housing, connected to said operating member and said head of the other of said cores to urge the latter away from said element simultaneously with the movement of said first-mentioned core away from said element; and a member slidably attached to said housing for movement in a direction substantially parallel to that of said operating member, said arm of said operating member being slidably connected to said slidable member, whereby operation of the latter acts to separate said pole tips regardless of the position of said housing.

6. A device for retracting the pole tips of a pair of electro-magnets from an element between them, which includes: a housing adapted to receive said element; a pair of substantially co-axial electro-magnets mounted within said housing, each of said electro-magnets having an axially slidable core, the adjacent pole tips of said cores being adapted to bear against opposite sides of said element; an enlarged head formed on each of the remote ends of said cores; a spring extending between each of said heads and said housing to urge said cores toward said element; a T-shaped operating member slidably mounted in said housing with its stem generally parallel to the axes of said electro-magnets and its cross bar perpendicular thereto; rigid plate means on said cross bar extending beneath said head of one of said cores, movable with said operating member to move said core against the urging of said spring, away from said element; and plate means pivotally attached to said housing for rotation about an axis generally perpendicular to said axis of said electro-magnets, with one end of said plate means fitting into a notch in said stem of said operating member, and the other end fitting beneath said head of the other of said cores, whereby movement of said operating member pivots said plate means to move said last-mentioned core, against the urging of said spring, away from said element at the same time said first-mentioned core is moved away therefrom.

7. A device for separating the pole tips of a pair of electro-magnets adapted to be moved across an element between them, which includes: a supporting member; a housing mounted on said supporting member and movable with respect thereto adapted to receive said element; a pair

of substantially co-axial electro-magnets mounted within said housing and movable therewith, each of said electro-magnets having an axially slidable core, the adjacent pole tips of said cores being adapted to bear against opposite sides of said element; an enlarged head formed on each of the remote ends of said cores; a spring extending between each of said heads and said housing to urge said cores toward said element; a T-shaped operating member slidably mounted in said housing for movement along its axis of symmetry with its stem generally parallel to the axes of said electro-magnets and its cross bar perpendicular thereto; plate means on said crossbar extending beneath said head of one of said cores, movable with said operating member to move said core, against the urging of said spring, away from said element; plate means pivotally attached to said housing for rotation about an axis generally perpendicular to said axes of said electro-magnets, with one end of said plate means fitting into a notch in said stem of said operating member, and the other end fitting beneath said head of the other of said cores, whereby movement of said operating member pivots said plate means to move said last-mentioned core, against the urging of said spring, away from said element at the same time said first-mentioned core is moved away therefrom; and a member slidably attached to said housing for movement in a direction substantially parallel to that of said operating member, said stem of said operating member being slidably connected to said slidable member, whereby operation of the latter acts to separate said pole tips regardless of the position of said housing.

8. A device for retracting the pole tips of a pair of electromagnets from an element between them, which includes: a supporting member; a handle pivotally attached to said support; a plate slidably mounted on said support; an ear on said plate having a bifurcated end adjacent said handle; a projection on said handle engaging said bifurcated ear, whereby rotation of said handle slides said plate along said support; a housing adapted to receive said element; a pair of electro-magnets within said housing, having core members with pole tips adapted to bear against opposite sides of said element; an operating member actuated by said slidable plate for movement in a direction to retract one of said pole tips; means connecting said operating member to one of said pole tips to retract the latter; and pivoted means interconnecting said member and said remaining pole tip whereby movement of said operating member in one direction moves said remaining pole tip in the opposite direction, thereby separating said pole tips.

9. A device for retracting the pole tips of a pair of electro-magnets from an element between them, which includes: a supporting member; a handle pivotally attached to said support for movement in a plane perpendicular to the surface thereof; a plate slidably attached to said support for movement in a plane substantially parallel to said surface thereof; a bifurcated ear attached to said plate, extending perpendicular thereto adjacent said handle; a projection on said handle rotatable therewith, and extending into said bifurcated ear to move the latter and said slidable plate; a housing adapted to receive said element; a pair of substantially coaxial electro-magnets mounted within said housing, each of said electro-magnets having an axially slidable core, the adjacent pole tips of said cores being

adapted to bear against opposite sides of said element; an enlarged head formed on each of the remote ends of said cores; a spring extending between each of said heads and said housing to urge said cores toward said element; a T-shaped operating member slidably mounted in said housing with its stem generally parallel to the axes of said electro-magnets and its cross bar perpendicular thereto and connected to said slidable plate for operation thereby; rigid plate means on said cross bar extending beneath said head of one of said cores, movable with said operating member to move said core, against the urging of said spring, away from said element; plate means pivotally attached to said housing for rotation about an axis generally perpendicular to said axes of said electro-magnets, with one end of said plate means fitting into a notch in said stem of said operating member, and the other end fitting beneath said head of the other of said cores, whereby movement of said handle moves said operating member to pivot said plate means and move said last-mentioned core, against the urging of said spring, away from said element at the same time said first-mentioned core is moved away therefrom.

10. A device for simultaneously retracting the pole tips of a pair of electro-magnets adapted to be moved across an element between them, and a pair of electro-magnets which are immovable across said element, which includes: a supporting member; an actuating member movably attached to said supporting member; a movable housing mounted on said supporting member for movement across said element; a pair of electro-magnets mounted within said movable housing for movement therewith, said electro-magnets having core members with pole tips axially movable through said electro-magnets and adapted to bear against said element; operating means mounted in said movable housing for movement therewith in one direction, and movable in a substantially perpendicular direction to separate said pole tips, said operating means being connected to said actuating member for sliding movement with respect thereto in said first direction; a housing fixed to said supporting member; a pair of electro-magnets mounted within said housing, having core members with pole tips axially movable therethrough and adapted to bear against said element; and operating means mounted in said fixed housing to separate said last-mentioned pole tips, and connected to said actuating member, whereby operation of said actuating member simultaneously separates both of said pairs of pole tips from said element, regardless of the position of said movable housing.

11. A device for simultaneously retracting the pole tips of a pair of electro-magnets adapted to be moved across an element between them, and a pair of electro-magnets which are immovable across said element, which includes: a supporting member; a handle pivotally attached to said support; a plate slidably mounted on said support; an ear on said plate having a bifurcated end adjacent said handle; a projection on said handle engaging said bifurcated ear, whereby rotation of said handle slides said plate along said support; a movable housing adapted to receive said element and be moved thereacross; a pair of electro-magnets within said housing and movable therewith, having core members with pole tips adapted to bear against opposite sides of said element; an operating member within said housing and movable therewith, connected to said

5 slidable plate for sliding movement with respect thereto in a direction substantially perpendicular to said movement of said plate; means connecting said operating member to one of said pole tips to retract the latter; pivoted means interconnecting said member and said remaining pole tip whereby movement of said operating member in one direction moves said remaining pole tip in the opposite direction, thereby separating said pole tips; a housing fixed to said supporting plate and adapted to receive said element; a pair of electro-magnets within said fixed housing, having core members with pole tips adapted to bear against opposite sides of said element; an operating member within said fixed housing and connected to said slidable plate; means connecting said last-mentioned operating member to one of said last-mentioned pole tips to retract the latter; and pivoted means interconnecting said last-mentioned operating member and the other of said last-mentioned pole tips whereby movement of said operating member moves said last-mentioned pole tip in the opposite direction, thereby separating said last-mentioned pole tips.

12. In a magnetic recording and/or reproducing machine, the combination of: a housing, a pair of substantially co-axial electromagnets mounted in said housing at a fixed axial spacing distance, there being a pasageway through said housing between said electromagnets for passage of a linear magnetic recording element, axially slidable cores in said electromagnets adapted to bear on opposite faces of said recording element, spring means urging said cores into tight pressural engagement with said record element, core retraction means movable in a given direction to retract said cores, operative connections between said means and said cores causing said cores to be simultaneously retracted by virtue of a given movement of said means, spring means urging said core retraction means toward a position wherein it retracts said cores, and operating means for said core retraction means having a lost motion operative connection with said core retraction means.

13. A combination as defined in claim 12, wherein said housing for said electromagnets is movable in a transverse direction relative to the linear recording element, and wherein said core retraction means includes a first portion movable with said housing and operatively connected with said cores, and a second portion connected to said operating means movable by the latter through said lost motion connection in a direction at right angles to the movement of said housing, said first portion of said retraction means having a sliding operative engagement with said second portion of said retraction means.
